UNITED STATES PATENT OFFICE

ALBERT JOHN KAUFFMAN, OF NEW YORK, N. Y., ASSIGNOR TO TRANS AD INCORPORATED, OF NEW YORK, N. Y., A CORPORATION OF NEW YORK

CHANGEABLE EXHIBITOR

Application filed December 5, 1931. Serial No. 579,273.

In changeable exhibitors, especially of the type employing indicia carrying cards or plates, it is a desideratum to permit facile and expeditious replacement of the cards; especially is this true with power operated exhibitors, where difficulty is usually experienced in stopping the mechanism at a point of vantage and in removing the cards or plates without a considerable loss of time and inconvenience. It is therefore an object of the present invention to provide a removable connection between the carriage and power means to permit manual operation of the carriage and to provide card embracing means at both ends of the exhibitor which are also manually movable without the aid of instruments to permit the cards to be removed from both ends of the exhibitors.

Another object of the invention is to provide an exhibitor in which the cards are arranged in groups with yieldable means to retain each group within a predetermined zone, yet permitting the cards to be selectively urged outside of said zone when pressure is exerted on a card during transfer thereof from one group to another.

Still another object of the invention is to provide a changeable exhibitor which is positive in its operation and the moving parts thereof embraced by anti-friction means to permit operation of the card transfer mechanism with a minimum resistance, the exhibitor being constructed throughout to render the same practically noiseless during its operation.

It is to be understood that the exhibitor of the present invention is susceptible of a variety of uses and I am aware that various changes may be made therein, without departing from the spirit and scope of the invention. I have, however, herein outlined one mode which I have found to be advantageous in carrying out the principle of the invention, which is shown in the accompanying drawings, wherein

Fig. 1 is a front elevational view, partly in section, of an exhibitor constructed in accordance with the present invention;

Fig. 2 is a longitudinal section view thereof, taken above the indicia carrying cards

or plates and showing the latter in top plan; Fig. 3 is a cross-sectional view, taken on the line 3—3 of Fig. 2, looking in the direction of the arrows;

Fig. 4 is a cross-sectional view, taken on the line 4—4 of Fig. 2, looking in the direction of the arrows;

Fig. 5 is a detail, fragmentary plane view of the carriage operating mechanism and the bottom of the exhibitor frame;

Fig. 6 is a fragmentary perspective view of the indicia plate carrying table or platform, showing the carriage associated therewith;

Fig. 7 is a longitudinal, fragmentary sectional view, taken along the line 7—7 of Fig. 3, looking in the direction of the arrows;

Fig. 8 is a detail fragmentary top plan view of the exhibitor showing to advantage some of the indicia bearing cards and the means employed for selectively moving the same;

Fig. 9 is a detail fragmentary cross-sectional view through the bottom of the carriage, showing to advantage the manner of connecting the carriage to the power means;

Fig. 10 is a detail perspective view of the bearing block and bearing pin forming the connecting unit between the power chain and carriage;

Fig. 11 is a perspective view of one of the card transfer dogs; and

Fig. 12 is a fragmentary perspective view of one of the yieldable spring abutments used between the groups of cards or plates.

The device of the present invention embodies a frame, generally designated 13, which in the present instance, is shown to be of rectangular configuration and embodies a pair of base blocks 14 and top blocks 15. The frame also embodies rods or bars 16, the ends of which are detachably mounted in the blocks 14. A rod or bar 17 rises upwardly from the upper face of each of the blocks 14 and has its upper terminal engaged in the blocks 15. Said blocks 15 also receive the opposite terminals of rods or bars 18, the latter being arranged in parallelism to the rods or bars 16.

On the rods 16 I sleeve a pair of bearings 19, which are intermediate the ends of the rods and remote from the base blocks 14. The bearings 19 support the opposite ends 5 of a cradle 20, in which an operating chain 21 is mounted. A shaft 22 extends upwardly from each of the bearings 19 and extends through the bottom of the cradle 20. Each shaft 22 is equipped with a sprocket wheel 23, which is suitably spaced from the bed 10 of the cradle. The sprocket wheel may be held from displacement by a retaining screw 24. A sprocket chain 25 is trained about the wheels 23 and carries a bearing block 26. The bearing block is provided on its 15 under face with a longitudinally extending groove 27, in which a roller bearing pin 28 is mounted to ride. The pin 28 also serves to connect a pair of the links of the chain 25. Mounted above the chain 21 and in spaced 20 relation thereto, is an indicia bearing card or plate receiving table, generally designated 29, which comprises an inverted U shaped base 30 and a superimposed platform 31, the lateral margins of the platform being bent 25 upwardly at right angles to prevent lateral displacement of the indicia bearing cards, in a manner more fully hereinafter set forth. The sides of the inverted U base 30 are 30 indented inwardly to provide ball races 32, which complement similarly formed races 33, formed in the sides of a U shaped carriage 34. It will be noted that the end rods or bars 17 project upwardly through the 35 ends of the base 30 and platform 31, the sides of the base being housed within the carriage 34, but sufficiently spaced therefrom to accommodate ball bearings 35, the latter being mounted in the races 32 and 40 33. The under face of the carriage 34 is provided with guide flanges 36 which are adapted for the reception of ribs 37, formed on the opposite sides of the bearing block 26. It consequently becomes apparent that 45 the power chain 21 is connected to the carriage 34 through the medium of the block 26 and pin 28. When in this position, rotation of the chain 21 imparts movement to the carriage 34 in a manifest manner, to reciprocate it back and forth between the 50 end rods 17 of the exhibitor frame 13. When it is desired to disconnect the power means from the carriage, the block 26 and pin 28 are removed, thereby permitting the carriage 34 to be manually operated.

A channel plate 38, which complements the platform 31, is mounted in the top of the frame 13, between the top rods 18 and extends in parallel relation to said platform throughout the length of the frame. The platform 31 is adapted to receive a plurality of indicia bearing cards or plates 39 which are preferably arranged in groups on the opposite sides of the transverse center line 60 of the exhibitor frame, as shown to ad-

vantage in Fig. 2. The cards or plates 39 are slidable between the platform 31 and channel plate 38 and may be engaged and/or disengaged through the opposite ends of the latter, beyond the sides of the end rods 17. Center blocks 40 are interposed between the groups of cards 39, one block being mounted on the platform 31, a similar block being carried by the channel plate 38. The ends of the blocks 40 fall short of the 70 opposite sides of the platform and channel plate to provide a clearance space sufficient to permit the passage of one of the cards or plates 39.

During the exhibition of the cards or plates, it is desirable to selectively transfer a card or plate from one group to the other and vice versa. For this purpose I mount on each side of the carriage 34, a bracket 41, in which a dog 42 is journaled. Each of the dogs 42, in the present instance, is shown to consist of a lever, one end of which is bent at right angles to extend over the upper margin of the platform 31 in order to impinge against a plate or card 39, as illustrated to advantage in Figs. 2, 4 and 6. Each dog is held in yieldable engagement with a card or plate by means of a spring 43, which is coiled about the shank of the dog, having one end thereof anchored to 90 said shank and the opposite end secured to the bracket 41. Movement of each dog in a direction counter to the direction of travel of a plate or card 39 is prevented by a stop 44, carried by the shank of the dog, which bears against the bracket 41, as illustrated to advantage in Fig. 4. It will consequently be apparent that when the carriage 34 is moved in the frame, the outermost card in one group of plates is moved toward the other group, while reverse movement of the carriage brings the other dog into play for transposing the innermost card of the opposite group to the other end of the casing. As advantageously illustrated in Fig. 2 of 100 the drawings, the group of plates at one end of the frame is urged forwardly by suitable means, such for instance, as flat springs 45, while the group of plates at the opposite end of the frame is urged rearwardly by 105 suitable means, such as flat springs 46. In this way the cards or plates are at all times held in position for selective interception by the dogs 42.

It is desirable to retain each group of 110 cards or plates compactly within a predetermined zone between the blocks 40 and a point remote from the end of the platform 31. For this purpose I employ flexor brackets, generally designated 47, one of which is 125 mounted at each end of the frame. Each flexor bracket comprises a bolt 48 which is slidably mounted through an end bar or rod 17 and has its opposite terminal engaged with side plates 49, the latter embracing 130

a roller 50 between its free terminals. It will be noted, especially upon reference to Figs. 1 and 2 of the drawings, that the free ends of the flexor brackets are arranged to lie within the confines of the end rods 17 and the rollers 50 of the flexor brackets are normally urged into engagement with the outer ends of the cards 39 by reason of the springs 51. One of each of the springs 51 is 5 helically wound around the bolt 48 on one side only of the rod 17, as shown to advantage in Fig. 4. One end of each spring is anchored to one of the side plates 49 and the opposite end secured to the end rod 17. 10 By mounting the spring 51 of each bracket on one side only of the rod 17, it will be understood that said bracket 47 may be moved laterally to provide a clearance space at 15 one side of the said rod 17, to permit engagement or removal of the cards 39. Furthermore, since the flexor brackets 47 are yieldable, it is apparent that in the transfer of a 20 card from one group to the other, the card being transferred may move beyond the 25 normal zone of the card group, as shown at the left side of Fig. 1 of the drawings. As soon, however, as the carriage reaches its terminus, pressure on the card is released and the latter forced inwardly into parallel 30 relation with the remaining cards of the group by the expansive action of the flexor bracket.

Since clearance spaces are provided beyond the ends of the center blocks 40, to permit the passage of the selective cards, it becomes necessary to provide means to prevent casual movement of cards through these spaces and with this end in view, I mount a pair of abutments 52 in the blocks 40. As 40 shown in Fig. 2 of the drawings, each block 40 is adapted to be provided with a longitudinally extending recess 53, the sides of which are straight, the recesses being adapted to receive the squared ends 54 of pintles 45 55. Each of the abutments 52 preferably consists of a plate, one margin of which is coiled about one of the pintles 55, the opposite margin thereof being provided with transversely extending slots 56 adjacent the 50 opposite ends of the abutment. The portion of each abutment beyond the slots 56 is bent outwardly at right angles to provide a finger 57. Each of the abutments 52 is normally urged outwardly over the opposite sides of 55 the platform 31 by a spring 58, which is coiled on the pintle 55 and anchored thereto and to the abutment. The pintles 55 are free to relatively move in the recesses 53, but are normally urged apart. For this purpose 60 I have mounted a spring 59 in each recess 53, the opposite ends of the spring bearing against the extremities of the pintles. The free margins of the abutments normally extend outwardly toward the sides of the platform 65 31, in which position the pintles are

in the extremities of the recesses 53 and the peripheries of the portions of the abutments which are coiled about the pintles overhang the ends of the center blocks 40. In this position the finger 57 of one abutment is 70 directly in back of the outermost card of one group, while the finger of the other abutment is directly in back of the innermost card of the other group. It will be apparent that, in this position, reverse movement of these cards beyond the blocks 40 is prevented. However, when the selected cards are moved in harmony with the movement of the carriage, the abutments 52 will be 75 impinged by the selected plates or cards and urged inwardly against the resistance of the springs 59. As soon as the selected plates or cards have been transferred, the abutments, under the expansive action of the 80 springs 59, are re-urged outwardly to the 85 outer termini of the recesses 53 of the center blocks.

For the purpose of illuminating the cards 39, I provide illuminating agents which are 90 preferably mounted, in any desirable manner, on the front upper rod 18. In the present instance, for this purpose, I provide twin lights 60, mounted above each card, preferably intermediate the ends of the latter, the lights projecting outwardly from the 95 rod 18 and being uniplanar therewith. The lights may be secured to the rod in any desired manner and may be illuminated from any desired source of energy.

In use of this device, it is preferred to 100 place the power chain 21 in operative connection with a suitable source of energy and for this purpose, one of the shafts 22 is extended for engagement with a drive means. Rotation of the chain imparts movement to 105 the carriage 34, which correspondingly moves the dogs 42 and transfer of the cards is effected in the manner already described.

The drawings illustrate a preferred form 110 of the invention, but I am of course, aware that changes may be made in the structure within the scope of the claims hereto appended.

What is claimed is:

1. In a changeable exhibitor, a table 115 equipped with indicia bearing cards, a carriage on the table, and means engaged with the carriage for moving the same, and a detachable block operatively connecting said carriage and means.

2. A changeable exhibitor including a frame, a table mounted on the frame and equipped with indicia bearing cards, means to slide said cards on the table, and means 120 pivotally mounted in the ends of the frame and projecting inwardly over the ends of the table in the path of the cards to confine the latter within a predetermined zone 125 on the table, said means being yieldable 130

to permit sliding movement of a card, under pressure, beyond said zone.

3. A changeable exhibitor including a frame, a table mounted on the frame and equipped with a block intermediate its ends, a guide arranged on the frame in parallel relation to the table and equipped with a block paralleling the table block, indicia bearing cards arranged in groups on the opposite sides of said blocks and movable singly beyond the ends of the latter, and relatively movable means mounted in the blocks to prevent movement of the cards in one direction, said means being yieldable to permit movement of the cards in the opposite direction.

4. A changeable exhibitor including a frame equipped with a platform and a guide arranged on the frame in parallel relation to the platform, indicia carrying cards slidably mounted between the table and guide, means mounted on the opposite ends of the frame to limit movement of the cards toward the outer ends of the frame, said means being laterally displaceable to permit engagement of the cards with and removal of the same from the table.

5. A changeable exhibitor including a table equipped with groups of indicia bearing cards, said table embodying an inverted U-shaped base subjacent the table top, a carriage engaged, by antifriction means, to said

base, out of contact with said cards, and dogs mounted on the carriage and overhanging the table to selectively engage the cards of each group to transfer them during movement of the carriage.

6. A changeable exhibitor, including a frame, the base of which includes a pair of bars, a table mounted on the frame equipped with groups of indicia bearing cards, a carriage slidably mounted on the table, dogs mounted on the carriage and overhanging the table to selectively engage the cards of each group to transfer them during movement of the carriage, a cradle mounted on the base bars of the frame subjacent the table, power means movably mounted in the cradle and in operative connection with the carriage, and a power shaft depending from the power means through said cradle.

7. A changeable exhibitor including a table for carrying groups of cards, said table comprising a platform and a base, the latter extending along the longitudinal center of the platform in spaced relation to the sides thereof, a carriage embracing said base, antifriction means slidably connecting the carriage and base, and means on said carriage and projecting upwardly at the sides of the platform and over the top of the latter for engagement with said cards.

ALBERT JOHN KAUFFMAN.
